VAULTING POLE

Robert F. Carpenter, Cleveland, Ohio

Application April 12, 1935, Serial No. 16,103

2 Claims. (Cl. 272—59)

This invention relates to an improved form of vaulting pole.

Heretofore, vaulting poles have been formed of wood and they have necessarily been of comparatively large diameter in order to prevent splintering or breaking and the consequent danger of injury to the athlete. Furthermore, solid wooden poles of such large diameter are quite heavy and awkward to handle.

10 It is therefore the object of the present invention to provide a vaulting pole of light weight metal of hollow tubular form which will possess sufficiently large diameter throughout the bottom part thereof and which may be formed of reduced 15 diameter in the top part thereof so as to afford proper balance and facilitate handling of the same and which is also suitably reinforced.

A further object is to devise a vaulting pole 20 of hollow tubular form which throughout the upper part thereof is swaged so as to produce a virtually tapering form throughout the upper part with the diameter reduced toward the upper end so as to facilitate handling of the same and at the same time to afford means of reinforcing the same.

25 Other objects will appear from the following description and claims when considered together with the accompanying drawing.

Fig. 1 illustrates a vaulting pole which is constructed in accordance with my invention and 30 which is broken in length for convenience in illustration;

Fig. 2 is a partial view of the top end portion 35 of my improved vaulting pole with part broken away;

Fig. 3 is a similar view of the bottom end portion thereof; and

Fig. 4 is a partial view illustrating in section 40 the swaged form of my improved vaulting pole throughout the upper part thereof.

It is to be understood that the present disclosure is merely for purposes of illustration and that various modifications may be made without departing from the spirit of the present invention 45 as herein set forth and claimed.

In the construction of my present improved form of vaulting pole, a hollow cylindrical tube 50 of aluminum alloy or other suitable light weight metal is swaged throughout the upper part thereof so as to form the successive cylindrical portions 1 which are of gradually reduced diameter toward the top end of the pole while the bottom end portion 2 of the pole is of uniform cylindrical form throughout the extent thereof. The 55 shoulders between the successive cylindrical por-

tions 1 are indicated by reference numeral 3 and the shoulders serve as a means of reinforcement for the upper part of the pole which in effect is thus given a tapering form.

The top end of the pole is closed by the cap 4 5 which is inserted into the open end of the tubular pole and riveted in place while the bottom end of the pole is closed in like manner by means of the cap insert 5. It will be observed that these end closures are of convex form on their ends 10 so as to provide rounded top and bottom ends for the pole.

In one specific instance of construction, as a means of illustrating the manner in which the present invention may be employed, I have provided a hollow tube of aluminum alloy, the wall of which is .058 inch in thickness. The outer diameter of the bottom part 2 thereof is 1.750 inches, and the first reduced cylindrical portion 1 which adjoins the bottom part 2 of the pole is 1.736 inches in diameter while the next cylindrical portion 1 is 1.723 inches in diameter and the next cylindrical portion 1 is 1.704 inches in diameter, etc., to the top end of the vaulting pole. In this particular instance, the bottom part 2 of 20 the pole which is of uniform diameter is of eight (8) feet in extent while the swaged part of the pole comprises a succession of sixteen (16) cylindrical portions of seven (7) inches each in length, aggregating nine (9) feet and four (4) inches, 30 and the uppermost reduced portion of the pole which is eight (8) inches in length and has an outer diameter of 1.500 inches.

As above stated, it is to be understood that the present invention is not limited to the specific 35 measurements just recited but that this specific instance is described in detail merely for the purpose of explaining the actual construction of one particular form of the present invention.

The swaging of the pole may extend through- 40 out a greater or less portion thereof than is herein illustrated and the swaged sections may be of greater or less length and the difference between the diameters of the successive swaged sections may also be greater or less than that herein il- 45 lustrated.

Thus, with my invention, it is possible to produce a vaulting pole which may have a bottom part of comparatively large diameter and increased strength while the upper part thereof 50 may have a virtually tapering form so as to afford proper balance and facilitate handling by the athlete while at the same time the upper part is afforded substantial reinforcement by the swaged form which is given thereto.

5 My improved form of vaulting pole may thus be made of such dimensions as will afford greatly increased dependability as well as an extreme degree of safety for the athlete while at the same time the weight of this vaulting pole will be sufficiently light and suitably balanced to facilitate skillful handling by the athlete. It also possesses the proper degree of whip.

10 Furthermore, my invention permits ready manufacturing of vaulting poles without any uncertainty as to the quality of material; there is precluded the inherent danger of faulty material, and there is also eliminated the difficulty of obtaining wood suitable for this purpose.

15 A pole made according to my invention may be kept by the athlete throughout his entire career and the pole will always feel familiar to him which can not be true in the case of wooden poles which are being continually replaced and 20 no two of which are exactly the same.

What I claim is:

1. A vaulting pole comprising a one-piece hollow tube of light-weight metal, said tube having at least its upper part formed with a succession of cylindrical sections of gradually reduced diameters towards and including the top end thereof, whereby the top end is smaller in diameter than the bottom end.

2. A vaulting pole comprising a one-piece hollow tube of light-weight metal, said tube having 10 its bottom part of cylindrical form of uniform diameter throughout substantially one-half the entire extent thereof, and having the upper part thereof swaged into successive cylindrical sections of gradually reduced diameters towards and 15 including the top end thereof, and a cap closure secured within each of the two ends thereof.

ROBERT F. CARPENTER.
